Her Attorneys.

Patented Oct. 16, 1928.

Des. 76,601

UNITED STATES PATENT OFFICE.

KATHLEEN BOE, OF ST. LOUIS, MISSOURI.

DESIGN FOR A SCORE CARD.

Application filed April 4, 1927. Serial No. 21,451. Term of patent 3½ years.

To all whom it may concern:

Be it known that I, KATHLEEN BOE, a citizen of the United States, residing in the city of St. Louis and State of Missouri, have invented a new, original, and ornamental Design for a Score Card, of which the following is a specification, reference being made to the accompanying drawing, forming part thereof.

The drawing is a front elevational view showing my new design.

I claim:

The ornamental design for a score card, as shown.

KATHLEEN BOE.
